(57) **CLAIM**

The ornamental design for a carbonator, as shown and described.

DESCRIPTION

FIG. 1 is an isometric view of a front and left side of an ornamental design for a carbonator;

FIG. 2 is an isometric view of the rear and left side of the carbonator of FIG. 1;

FIG. 3 is a front elevational view of the carbonator of FIG. 1;

FIG. 4 is a left side elevational view of the carbonator of FIG. 1, the right side elevational view being a mirror image thereof;

FIG. 5 is a rear elevational view of the carbonator of FIG. 1;

FIG. 6 is a bottom plan view of the carbonator of FIG. 1; and,

FIG. 7 is a top plan view of the carbonator of FIG. 1.
